UNITED STATES PATENT OFFICE.

ARTHUR E. WILLIS AND REUBEN M. WILLIS, OF CHANUTE, KANSAS.

SPRING PITMAN.

Application filed September 9, 1924. Serial No. 736,799.

To all whom it may concern:

Be it known that we, ARTHUR E. WILLIS and REUBEN M. WILLIS, citizens of the United States, residing at Chanute, in the 5 county of Neosho and State of Kansas, have invented certain new and useful Improvements in Spring Pitmen, of which the following is a specification.

This invention appertains to drilling rigs 10 and more particularly to the pitman for operating the walking beam thereof.

The primary object of the invention is to provide an improved pitman for connection with the walking beam of a drilling machine 15 which is so constructed as to cushion the jar between the walking beam and the operating crank of the machine when the wrist pin on the crank of the machine starts on its downward stroke and when the weight of the line 20 and tools is on the walking beam, thereby effectively reducing the vibration of the whole machine and enhancing the life thereof.

Another object of the invention is to provide 25 a cushioned pitman rod of the above character embodying means for preventing rebound of the pitman after the cushioning of the jar, so as to effectively eliminate all vibration of the pitman rod.

A further object of the invention is to provide 30 a novel pitman embodying a sliding block to which the wrist pin of the drive crank is connected, the block being cushioned by suitable spring means at its upper and lower ends to effectively eliminate shock 35 and rebound.

A further object of the invention is to provide 40 an improved pitman of the above character which is particularly adapted for use when drilling with a wire line, but which is acceptable for use when drilling with a flexible rope line, the pitman being so constructed as to be durable and efficient in use, simple and easy to manufacture, and to permit 45 the same to be placed upon the market and incorporated with a drilling machine at a small cost.

With these and other objects in view, the 50 invention consists in the novel construction, arrangement and formation of parts, as will be hereinafter more specifically described, claimed, and illustrated in the accompanying drawings, in which drawings:

Figure 1 is a side elevation of the im-

proved pitman showing parts thereof broken away, and 55

Figure 2 is an edge elevation of the same showing parts thereof broken away.

Referring to the drawings in detail, wherein similar reference characters designate corresponding parts throughout the several views, the letter A generally indicates the improved pitman rod, which comprises an upper solid wooden block 5 to which is secured the iron stirrup 6, which fastens on top of the walking beam 7 under the tail board 8 thereof. This solid wooden block 5 has bolted thereto as at 9 the frame 10 which can be formed of strap iron or the like. As shown this frame 10 depends from the wooden block 5 and has slidably mounted therein the solid wooden slide block 11, the purpose of which, will be hereinafter more fully described. The frame 10 embodies side plates 12, a connecting bottom 75 plate 13, and a connecting top plate 14. As clearly shown in the drawings the side plates 12 gradually converge inwardly toward each other and towards the ends of the top plate 14. The lower end of the solid slide block 11 rests upon a flat metal plate 15 which is supported by a plurality of relatively heavy springs 16 which rest upon the lower plate 13 of the frame 10. These springs 16 constitute the cushion springs for reducing the 80 shock during the initial raising of the line and tool. In order to protect the springs and hold the same in position retaining plates 17 are bolted to the edges of the frame 10 as clearly shown in the drawings. The 85 upper end of the wooden slide block has fitted on its upper surface a metal wear plate 18 supporting a plurality of relatively heavy springs 19 which constitute the rebound springs. The upper ends of the springs 19 have resting on the same a wear plate 20 as clearly shown in Figure 1 of the drawings. The upper and lower springs 16 and 19 are 90 preferably packed with grease to keep the same well lubricated and to prevent deterioration thereof by crystallization.

A wedge key 21 formed either of wood or iron is provided for adjusting the tension of the springs and the side plates 12 of the frame 10 are provided with openings 22 for receiving the wedge and the lower surface of the wedge is adapted to rest upon the wear plate 20 as clearly shown in Figure 1 105

of the drawings. If so desired the lower face of the solid upper wooden block 5 may be beveled to conform to the wedge face of the key 21.

5 The wrist pin 25 of the drive crank 26 is adapted to be received between suitable upper and lower bearing blocks 27 and 28. As shown the lower bearing block 28 is secured rigidly in place to the slide block 11 10 by the use of suitable bolts or the like 29, the terminals of which are countersunk within the slide block. The upper bearing block 27 is slidably mounted within the slide block 11 and is adapted to be held in place by a 15 wedge key 29 which extends through suitable openings 30 formed in the side plates 12 of the frame 10 and the slide block 11 is provided with an opening for receiving the same. When it is desired to remove the 20 wrist pin 25 it is merely necessary to remove the wedge key 29 from its place and the upper bearing block 27 will be raised through the medium of a spring 31 having its lower end fastened to the block 27 and its 25 upper end to the slide block 11.

In operation of the improved pitman rod, all jar and the like will be taken up by the springs 16 and rebound will be prevented by the springs 19. It thus can be seen that 30 the slide block 11 is cushioned at both of its ends. As stated the pitman is particularly adapted to be used with wire lines and when the pitman is used with wires lines no ill effect will be noted and will give the same 35 results as if rope were being used.

If rope is being used instead of wire lines a bolt 35 can be utilized for holding the slide block against movement and as shown this bolt 35 extends through the side plates 12 of 40 the frame 10 and through the slide block 11 holding the same against movement relative to the frame.

Changes in details may be made without departing from the spirit or the scope of 45 this invention, but

What we claim as new is:

1. A pitman rod comprising a solid wooden block, a frame receiving the block

and secured thereto and depending therefrom, a walking beam receiving stirrup secured to the block extending above the frame, a slide block slidably mounted within the frame and disposed above the upper block, a set of cushioning springs arranged between the lower end of the slide block 55 and the frame, means retaining the springs in position, an upper set of rebound springs arranged on the upper face of the slide block, a wear plate disposed on the upper end of the rebound springs, a wedge key disposed intermediate the wear plate and the upper solid block for tensioning the springs, and bearing blocks carried by the slide block for receiving the wrist pin of a drive crank.

2. A cushioned pitman rod for use in well drilling machines comprising a solid upper block, a hollow frame receiving the block and depending therefrom, means for rigidly connecting the block with the frame, a stirrup connected to the block and extending above the frame, a slide block slidably mounted within the frame below the upper block, cushioning springs arranged between the lower end of the slide block and the frame, means for retaining the springs in position, a wear plate on the upper end of the slide block, a set of rebound springs disposed upon the wear plate, a top wear plate fitted upon the upper ends of the rebound springs, a wedge key disposed intermediate the top wear plate and the upper solid block, a lower bearing block rigidly carried by the slide block, an upper bearing block slidably carried by the slide block, the bearing blocks being adapted to receive a wrist pin of a drive crank shaft, means for normally tending to raise the upper slide bearing block, and a wedge key slidably associated with the frame for engaging the slide block and the sliding upper bearing block.

In testimony whereof we affix our signatures.

ARTHUR E. WILLIS.
REUBEN M. WILLIS
